UNITED STATES PATENT OFFICE.

EDWIN M. BASSLER, OF MILWAUKEE, WISCONSIN.

RADIATOR.

1,368,318.

Specification of Letters Patent. Patented Feb. 15, 1921.

Application filed March 21, 1917. Serial No. 156,248.

To all whom it may concern:

Be it known that I, EDWIN M. BASSLER, a citizen of the United States, and resident of Milwaukee, in the county of Milwaukee, 5 and State of Wisconsin, have invented a new and useful Improvement in Radiators, of which the following is a specification.

This invention relates to heating coils or radiators and relates particularly to heating coils or radiators of the type comprising a header, the interior of which is divided into compartments by a partition, radiating pipes secured in an outer wall of said header the inner ends of which are in 10 open communication with one compartment of said header and the outer ends of which are closed, and open-ended pipes secured in the partition wall of said header, which extend into the radiating pipes secured in 15 said header, the attached ends of which are in open communication with the compartment of the header other than that with which said outer radiating pipes communicate.

25 The object of the invention is to provide a header for a radiator of the type specified, constructed and arranged for effectively draining itself of water of condensation; and in which, also, the steam entering the 30 header will operate to maintain the water of condensation at a sufficiently high temperature to prevent it from freezing even in very severe weather.

To effect the objects of the invention, a 35 radiator of my invention comprises the various features and details of construction hereinafter described and claimed.

In the accompanying drawing, in which my invention is fully illustrated,

40 Figure 1 is a side view of my improved radiator, showing the header and a portion of the pipes or tubes in section, the header being disposed horizontally.

Fig. 2 is a plan section thereof on the 45 line 2—2 of Fig. 1.

Fig. 3 is an end view thereof from the position 3—3 of Fig. 1.

Fig. 4 is a sectional end view thereof on the line 4—4 of Fig. 1.

50 Fig. 5 is a side view, partly in section, of a radiator embodying my invention, showing the header disposed vertically; and

Fig. 6 is a fragmentary view of the end 55 thereof.

Referring now particularly to Figs. 1 to 4 of the drawing, A designates the header of a radiator of my invention, the interior of which is divided by a longitudinal partition A' into compartments a, a'. 60

As shown, said header A is disposed horizontally and secured in the top wall 1 thereof are tubes 2, the inner ends of which are in open communication with the compartment a of said header and the outer ends 65 of which are closed; and secured in the partition A' are open ended tubes 3 which are smaller than the inside diameters of the tubes 2 and extend into said tubes, being preferably of such length that they will extend to 70 within a short distance of the closed ends of said tubes 2. Both ends of the tubes 3 being open, said tubes thus connect the compartment a' of the header with the interiors of the tubes 2 adjacent to their outer, closed 75 ends and, through said tubes 2, with the compartment a of said header A.

The pipes 2 are of proper size to provide adequate heating surface and to produce a 80 desired velocity of steam circulation therein to secure efficient and economic operating conditions.

Formed at one end of the header A is a chest 4 the interior of which is divided by an angular wall 5 into chambers 6 and 85 7, of which the chamber 6 is in open communication with the compartment a' of the header A and is adapted to be connected by a pipe 8 with a source of steam supply, not shown, and the chamber 7 is in open 90 communication with the compartment a of the header A and is provided adjacent to its bottom side with a drain connection 9. To provide for draining the steam compartment a' of said header and the chamber 6 of the chest 4, said chest 4 preferably extends below the bottom wall of said header A and the chamber 7 of said chest is extended beneath the bottom wall of the chamber 6 and is connected with said chamber 95 10 by means of a drain hole 10 formed in the bottom wall of said chamber 6. Preferably the bottom of the chamber 6 is below the bottom of the compartment a', whereby water of condensation accumulat- 105 ing in the chamber 6 will form a water seal for the drainage opening 10, thus preventing the escape of steam from the chamber 6 to the drainage chamber 7. It is found in practice that, due to the low steam pres- 110

sure used in radiators of this type, an effective seal can be provided by making the drainage hole 10 of small size.

In practice, I effect the object of my invention as it relates to preventing freezing of the water of condensation in severe weather, by the angular shape of the partition wall 5, whereby the return compartment of the chest 4 extends on two sides 10 of the steam compartment 6, thus providing a relatively large radiating surface maintained at a high temperature by the steam entering the compartment 6, which will operate, in an obvious manner, to maintain the 15 water of condensation contained in said return compartment at a correspondingly high temperature, and will effectively prevent freezing thereof under all usual conditions of use.

20 In the preferable construction shown, both the upper side of the partition A' and the inner side of the bottom wall of the header A decline toward the chest 4, so that all water of condensation will drain from 25 both of said compartments a and a' into said chest, the water of condensation from the compartment a passing directly into the chamber 7 while that from the compartment a' passes first into the chamber 6 and 30 thence through the drainage hole 10 into said chamber 7.

To prevent the air from becoming trapped in the radiator, which would prevent the steam from circulating therethrough, said 35 header is preferably provided with a usual air vent, consisting, as shown, of a hole or opening 11, formed through the top wall of the drainage chamber 7 of the chest 4 of said header.

40 My improved radiator may be supported by any desired or approved means, being preferably supported in such manner that it may expand and contract freely without being subjected to any stresses therefrom, 45 the relation being preferably such that the top side 1 of the header A will extend substantially horizontal and the bottom wall of said header and the partition A' will decline at a desired angle toward the chest 4.

50 As shown, said radiator rests loosely, adjacent to its ends, on the upper edges of inverted T-bars 12 and 13, the bases of which are secured to the floor or other supporting surface.

55 Said radiator is confined in position on said T-bars 12 and 13 by transverse ribs 14 formed on the under side of said header A, outside of and closely adjacent to which the T-bars 12 and 13 are designed to be positioned, whereby contact of said ribs 14 with the upper ends of said T-bars will limit the movement of said header A.

In the installation of radiators, it frequently happens that the vertical space 65 available for the radiator is limited, while

the available horizontal space is practically unrestricted, thus rendering it necessary to conform the vertical dimension of the radiator to the vertical space available and to correspondingly increase the horizontal dimension of the radiator, in order to provide the necessary radiating surface. 70

A radiator embodying my invention is particularly well adapted for use under the conditions described, its application merely 75 requiring the installation of the header A in upright instead of horizontal position, as shown in Figs. 1 to 4, and securing the circulating pipes therein so that they will project horizontally therefrom, said header being 80 made of a height to conform to the vertical space available and the heating pipes of any length necessary to provide necessary radiating surface.

This application of my invention is shown 85 in Fig. 5 of the drawings, in which A² designates the header as a whole, supported in upright position, and secured in and projecting horizontally from which are the outer and inner tubes 2' and 3' which communicate, respectively, with the compartments a^2 and a^3 of the header, the outer ends of the tubes 2' being closed and both ends of the tubes 3' being open. 90

As regards all of its essential features and 95 excepting minor details hereinafter described, the radiator shown in Fig. 5 is identical in construction with that shown in Figs. 1 to 4 of the drawing and will be readily understood by persons skilled in the 100 art from an examination of said Fig. 5 without a detailed description thereof.

Steam is admitted directly to the compartment a^3 of the header through a steam supply pipe 8' which opens through a lateral 105 wall of said header and the chest of the header A², designated 4', is provided with drain and vent openings 9', 10' and 11' corresponding to the drain and vent passageways 9, 10 and 11 shown in Figs. 1 to 4, but 110 the position of which is changed to correspond to the changed position of said header.

The outer ends of the pipes 2' are supported by upright plates 15 formed in which are holes 16 adapted to receive said pipes 2'. 115 Said plates 15 are supported in upright position by angles 17 at the lower edges thereof, which are secured to the floor by means of lag screws or the like. The number of supporting plates 15 may be varied as may 120 be considered desirable or necessary to properly support the pipes 2'.

For purposes of convenient reference and in order to distinguish the compartments of the headers and the chambers of the chests, the compartments a , a^2 of the headers will 125 be designated in the claims, return compartments, and the compartments a' , a^3 , steam compartments. And, in like manner, the compartments 6 and 7 of the chest will be 130

designated in the claims as the steam and return compartments thereof, respectively.

I claim:

1. A radiator comprising a header and a chest, partitions which divide said header and chest into steam and return compartments, the compartments of said chest communicating, respectively, with different compartments of said header, pipes which connect the compartments of said header, and a pipe which communicates with one compartment of said header and is adapted for admitting steam thereto, the relation being such that the compartments of said header will drain into the compartments of said chest with which they communicate, respectively, and the compartments of said chest being provided with drainage pasageways, the drainage passageway from the steam compartment being formed in the bottom wall thereof and discharging into the return compartment of said chest, the bottom of the steam compartment of said chest being lower than the bottom of the steam compartment of the header, the relation being such that the water which drains into said compartment will form a water seal for the drainage passageway from the steam compartment of said chest, substantially as described.
2. A radiator comprising a header and a chest, partitions which divide said header and chest into steam and return compart-

ments, the compartments of said chest communicating, respectively, with different compartments of said header, pipes which connect the compartments of said header, and a pipe which communicates with one compartment of said header and is adapted for admitting steam thereto, the relation being such that the compartments of said header will drain into the compartments of said chest with which they communicate, respectively, and the compartments of said chest being provided with drainage pasageways, the drainage passageway from the steam compartment discharging into the return compartment of said chest, the return compartment of said chest extending on two sides of the steam compartment thereof, whereby steam entering the steam compartment of said chest will maintain the water in the return compartment of said chest at a sufficiently high temperature to prevent freezing thereof, and the bottom of the steam compartment of said chest being lower than the bottom of the steam compartment of the header, the relation being such that the water which drains into said compartment will form a water seal for the drainage passageway from the steam compartment of said chest, substantially as described.

In testimony that I claim the foregoing as my invention, I affix my signature this 1st day of March, 1917.

EDWIN M. BASSLER.
